ELECTRIC RELAY.

1,185,332.

Specification of Letters Patent.

Patented May 30, 1916.

Application filed June 4, 1914. Serial No. 842,846.

To all whom it may concern:

Be it known that I, CHARLES PAUL GEORGES JOUBART, citizen of the Republic of France, residing at St.-Denis, Seine, France, have invented certain new and useful Improvements in Electric Relays, of which the following is a specification.

The electric time relays at present in use for causing the operation or release of any apparatus, in cases where the value of the current passing in a conductor or an electric machine exceeds a predetermined limit, operate with a rapidity which is greater the greater the overload. If a plurality of such relays located in series on the same circuit, are adjusted to produce, in a case of overloading, the breaking of the said circuit at different times at different intervals apart, it has been observed that when the overload exceeds a certain amount, the times of the operation or release vary very little as a function of the overload and have a tendency to coincide. In such circumstances it is impossible to rely upon a selective action of such relays. When however, automatic cut-outs are located in series along a conductor, it is extremely important that these devices shall be able to operate in a selective manner, irrespectively of the value of the current, that is to say, that for any value of the current the several releases shall always take place at different predetermined times in a strictly determined order. It is equally important that the times taken by the releases shall be longer the weaker the overloads; that is to say, in the case of cut-outs arranged in series these devices shall open less quickly in the case of a small overload than in the case of a great overload or of a short-circuit.

Now this invention has for its object to provide an improved relay, which is differentiated from the ordinary relays by the circumstance that it affords the above stated advantages.

One form of a relay constructed according to this invention is illustrated by way of example in the accompanying drawings, in which:

Figure 1 is a side view thereof, Fig. 2 is a cross section on the line $x-y$ of Fig. 1; and Fig. 3 shows a detail part.

As shown, the improved relay comprises

a disk A mounted loose on a shaft O. The disk A may be rotated on its axis by any suitable electric means which can produce therein a driving couple generated by the current flowing in the winding of the relay (rotating field, reaction of a coil short-circuited in the field, electro-magnetic action, etc.) To the disk A there is fixed a finger J connected to the shaft O by means of a spiral spring R, which is attached at one end to the said finger J and at its other end to a sleeve r fixed on the shaft O.

When the disk A is caused by the aforesaid driving couple to rotate in the direction of the arrow f (Fig. 1), the said disk will drive the shaft O through the medium of the spring R. This spring is normally stressed in such a manner that it will always move the finger J back into contact with a tappet P that is fixed on the sleeve r.

The shaft O has also fixed on it a toothed wheel E engaging a pinion B fixed on a shaft M that carries a fly governor C. The toothed wheel E has a finger S which is caused by the rotation of the shaft O, to bear upon the movable member of a contact device F D for effecting the closure of an auxiliary electric circuit actuating the apparatus controlled by the relay.

The hub of the disk A is constructed as a drum N on which is adapted to be wound a flexible wire or chain l carrying a weight K. When the disk is rotated as above stated in the direction of the arrow f, the wire l will be wound on the drum N and will thus lift the weight K. If now the disk A be released, the weight K will act to rotate the disk A backward until a stop T fixed to the said disk comes against an external fixed point, for instance the part U, which corresponds to the position of rest of the relay.

The operation of the improved relay is as follows:—When by the action of a driving couple generated by the current flowing in the winding of the relay, the disk A begins to rotate in the direction of the arrow f, it winds the wire l upon the drum N, and at the same time it drives the shaft O through the medium of the spring R, and with it, the toothed wheel E, the pinion B and the governor C. If the driving force of the disk A is smaller than the resisting couple produced by the governor C and the spring R, the members J and P will remain in con-

tact with each other, and the speed of rotation of the toothed wheel E will be a function of the driving couple of the disk A. The same relation holds good for the time 5 taken by the finger S to actuate the contact device F D of the auxiliary circuit. As soon as this contact takes place it will bring about the operation or the release of the apparatus controlled by the relay. In a case 10 where the overload occurring in the circuit of the relay disappears before the finger S has played the part allotted to it, it is to be understood that the various movable members hereinbefore referred to, will resume 15 their positions of rest under the action of the weight K, since the motion of the disk A in the opposite direction to that of the arrow f is transmitted to the shaft O and thence to the pinion B by the finger J that 20 is in engagement with the tappet P.

It is to be noted that by varying the weight K, it is possible to vary the value of the driving couple at which the disk A begins to be set in motion.

25 If when the disk A is rotating in the direction of the arrow f, the driving force of this disk is greater than the resisting couple produced by the governor C and the spring R, the latter will be stressed and the finger 30 J will leave the tappet P. In such a case the disk A will still drive the shaft O by means of the spring R, and consequently the toothed wheel E, the pinion B and the governor C, but then the time taken by the 35 finger S before it begins to actuate the contact device F D of the auxiliary circuit will depend on the resistance offered by the governor C. This time is increased and consequently the closure of the auxiliary circuit is 40 retarded, contrary to what is the case with the relays at present in use. In this latter case as in the former case above referred to, as soon as the overload in the circuit of the winding of the relay ceases, whether the 45 finger S has or has not effected the closure of the auxiliary circuit F D, the various movable elements or members will be caused by the action of the weight K to resume automatically their position of rest, the finger J of the disk A being brought again 50 into engagement with the tappet P fixed to the shaft O.

With a relay constructed according to the foregoing conditions, and by suitably selecting the weight K, and adjusting the value of the resistance couple produced by the governor C, which may be readily effected by changing the position or angle of the vanes of the said governor, it will be possible to 55 give to the time of release a strictly determined value.

Instead of acting simply upon the vanes of the governor C in order to effect the adjustment just mentioned, that is to say for 60 varying the time taken by the finger S for

closing the contact device F D of the auxiliary circuit, it is also possible to act upon the tension of the spring R.

If a plurality of these relays included in series in one and the same circuit are adjusted for varying times of release, a certain selective action taking place in the determined order will be produced.

It is to be understood that the fly governor C hereinbefore referred to is described 75 and shown simply by way of example and that any other device giving the same result, that is to say capable of producing a retarding couple, may be employed without departing from the nature of the present 80 invention. For instance, for this purpose there may be employed either a disk rotating in a magnetic field or forces due to gravity, friction, &c. Likewise the weight K may be replaced by a stressed spiral spring 85 fixed at one end and acting at its other end upon the disk K.

Instead of the drum N on which the cord l is wound, there may be employed a sort of spiral cam for receiving the said cord l 90 so as to vary automatically the effect produced by the weight K.

What I claim is:

1. An electric time relay comprising, in combination with a relay winding, a rotary member, means for rotating the same by current flowing in the said relay winding, a rotary shaft carrying said rotary member, a yielding means between said shaft and said rotary member to transmit 95 rotation from said rotary member to said shaft, a second rotary shaft geared with the said first rotary shaft, adjustable means on the said second rotary shaft to resist the rotation of the said rotary member, a contact device, means connected with the said first rotary shaft to close the said contact device, and means for returning all the movable parts to their initial positions. 100

2. An electric time relay comprising, in combination with a relay winding, a rotary member, means for rotating the same by a current flowing in the said relay winding, a rotary shaft carrying said rotary member, a yielding means between said shaft and said 105 rotary member to transmit rotation from the latter to the former, a second rotary shaft, a gearing coupling said second rotary shaft with the said first rotary shaft, a contact device, a projection on the gear mounted on the said first rotary shaft adapted to close the said contact device, an adjustable means on the said second rotary shaft to resist the rotation of the said rotary member in conjunction with the said yielding means, means 110 for returning all the movable parts to their initial positions, and a stop on said first rotary shaft to hold the said rotary member at rest. 115

3. An electric time relay comprising, in 120 combination with a relay winding, a rotary member, means for rotating the same by a current flowing in the said relay winding, a rotary shaft carrying said rotary member, a yielding means between said shaft and said rotary member to transmit rotation from the latter to the former, a second rotary shaft, a gearing coupling said second rotary shaft with the said first rotary shaft, a contact device, a projection on the gear mounted on the said first rotary shaft adapted to close the said contact device, an adjustable means on the said second rotary shaft to resist the rotation of the said rotary member in conjunction with the said yielding means, means 125 for returning all the movable parts to their initial positions, and a stop on said first rotary shaft to hold the said rotary member at rest. 130

combination with a relay winding, a rotary disk, means for rotating the same by current flowing in the said relay winding, a rotary shaft carrying the said rotary disk, 5 a spiral spring fast on said rotary shaft, a pin in said rotary disk engaging said spiral spring, a tappet on said rotary shaft forming an abutment for said pin, a second rotary shaft geared with said first rotary shaft, 10 a contact device, means connected with said first rotary shaft to close said contact device, adjustable vanes on said second rotary

shaft adapted to resist the rotation of said rotary disk in conjunction with said spiral spring, and means connected with the hub 15 of said rotary disk to return all the movable parts to their original positions.

In testimony whereof I have affixed my signature in presence of two witnesses.

CHARLES PAUL GEORGES JOUBART.
